Patented Sept. 9, 1924.

UNITED STATES PATENT OFFICE.

ROBERT N. MILLER, OF ALTOONA, PENNSYLVANIA.

BOILER.

Original application filed December 22, 1920, Serial No. 432,474. Divided and this application filed August 17, 1921. Serial No. 492,999.

To all whom it may concern:

Be it known that I, ROBERT N. MILLER, a citizen of the United States, and resident of Altoona, county of Blair, State of Pennsylvania, have invented certain new and useful Improvements in Boilers, of which the following is a specification.

This invention relates to vertical boilers and particularly to that type in which there is an outer cylindrical shell, upper and lower tube sheets, a series of vertical connecting tubes and flues between said tube sheets, a fire box in the lower part below the lower tube sheet and an outlet for smoke at the top. The present invention, in combination with the superheater construction claimed in my co-pending application, Serial No. 432,474, filed December 22, 1920, of which this application is a division, was designed primarily to produce and maintain the maximum constantly available steam power in a boiler construction of limited size. It was designed especially for use on locomotive cranes where the saturated fire tube type of boiler is usually used either with or without submerged tubes but where the clearance room within which such boilers are used is so restricted that their steaming capacity is usually below that called for by the service demands and where owing to the intermittent service called for by the crane engine the steam supplied to these units becomes saturated with moisture thus lowering the efficiency and causing excessive steam consumption per horse power hour. The present invention is intended to aid in meeting and overcoming these difficulties although it is of course not limited to that particular use. It includes means for properly regulating by the exhaust steam the circulation of the products of combustion to uniformly heat the flues, tubes and other parts of the boiler. The novel features will more fully appear from the following description and claims taken with the drawings.

In the drawings:

Figure 1 shows a boiler embodying the invention largely in vertical section;

Figure 2 is an enlarged plan view looking down on the exhaust nozzle; and

Figure 3 is a cross section of the nozzle on the line 3-3, Fig. 2.

As shown in the drawings the boiler construction includes the outer cylindrical shell

10, an upper tube sheet 11 and a lower tube sheet 12 and tubes and flues 13 arranged vertically connecting the two tube sheets and furnishing passageways from the fire box 14 to the smoke box 15. The lower tube sheet 12 has a down turned edge 16 secured to the upper edge of the tubular part 17 arranged centrally within the shell 10 and constituting the side walls of the fire box. The lower edge of this tubular part 17 is connected to the lower edge of the shell 10 by the bottom member 18 thus leaving a water space around the fire box. There is a door opening and door 19 for the fire box and the usual grate mechanism 20. The boiler further includes a cylindrical extension 60 suitably secured at its lower edge to an upstanding flange on a superheater header 21, hereinafter described, and a cover plate secured to the upper edge of 75 said extension.

The superheater header 21 is annular in form and fits between and connects the upper tube sheet 11 and the shell 10 serving as a marginal closure for the upper steam 80 space of the boiler. It is preferably made in one piece of cast steel and is provided on its upper inner margin with an upstanding flange 22 which fits and is riveted to the upturned marginal flange 23 on the upper tube sheet 11 and on its lower outer margin with a downwardly extending flange 24 riveted to the shell 10 at its top. At the lower end of flange 22 the header 21 has a horizontal portion 25 the lower surface of which is in 90 the same plane as the lower surface of the upper tube sheet 11 and in effect constitutes a continuation of it as the upper closure for the saturated steam space in the boiler. This horizontal portion is provided at intervals with vertical outlet openings 26 for saturated steam and the upper ends of these openings are preferably bored conically at 95 27 to make a steam tight joint with the inlet end of a superheater unit header as hereinafter explained. Below the horizontal portion 25 the header 21 extends downwardly in substantially cylindrical shape to the lower flange 24 but below that horizontal portion and above flange 24 an annular 105 superheated steam chamber 28 is formed entirely within it projecting inwardly into the saturated steam space of the boiler. This superheated steam chamber has inlet openings or passageways not shown lead- 110

ing vertically to and through the horizontal part 25 closely adjacent to the openings 26 and at their upper ends are preferably turned or ground to conical form to make 5 steam tight connection with the outlet header of a superheater unit. Superheated steam chamber 28 is furthermore provided with an outlet 31 leading to the exterior of the boiler and adapted to be connected by 10 steam pipes to an engine or for other uses.

The superheater units embody an inlet header 32 preferably made of cast metal and a similar outlet header 33 with a series of superheater tubes connecting them at intervals and extending down the flue of the boiler towards the fire box. These headers are in the form of return bends inlet header 32 having a downwardly extending end portion 34 with a conical outer end surface 35 adapted to fit in the conical upper portion 27 of the outlet opening 26 and outlet header 33 having a corresponding downwardly extending portion with a conical end surface fitting the conical upper portion of the inlet opening leading to the superheated steam chamber 28, and said headers are provided on their upper surfaces with integral projecting lugs adapted to enter sockets in the under surface of the metal clamps 37 secured 20 in place in the smoke box 15. These inlet and outlet headers for the superheater units are securely clamp bolted in place on the main superheater header casting. Each of the superheater unit headers extends inwardly over and close to the upper tube sheet 11 and each has on its under surface a series of bosses to which are connected preferably by welding the ends of superheater pipes 39. These superheater pipes as will be seen by 30 reference to Fig. 1 pass downwardly from the inlet unit header 32 in a vertical direction with a sharp bend or connection 40 at the lowest point and then back upwardly in parallel position to fit within one of the outlet flues of the boiler. The upper end is connected to a coupling member 41 and from that coupling a pipe leads downwardly in another flue of the boiler to a sharp lower bend 42 and then back to a connection with 40 the socket of the outlet unit header.

It will be observed that by the arrangement above described the saturated steam in the upper part of the boiler must pass through the superheater before it reaches the point of use, and that the superheating arrangement is a permanent integral part of the boiler and requires practically no excess space but gives largely increased heating surface.

As heretofore stated the smoke drum 15 extends entirely across the upper part of the boiler and contains the superheater unit headers 32 and 33 and other parts above tube sheet 11. In order to cause the proper distribution and circulation of the hot gases of

combustion from the fire box so as to uniformly reach and heat the various parts of the boiler a conical baffle plate 43 is secured to the under surface of the cover for the smoke box 15 around the central smoke stack 70 outlet 44 and terminates at its lower outer margin just above the superheater manifold. A steam exhaust pipe 45 leads into the smoke box 15 and is connected to a casting 46 containing a chamber 47 having an upper circular outlet 48 directly below the smoke stack outlet 44 and supported from the upper tube sheet 11 by the integral depending lugs 49. A casting 50 fits within the circular outlet 48 and has a vertical discharge opening or passageway 51 constituting the exhaust nozzle directed centrally towards the smoke stack outlet 44. On the interior of the exhaust discharge passageway 51 spiral inwardly projecting integral ribs 52 are formed so as 80 to create a whirling action of the exhaust steam and accompanying gases in the smoke box and out through the smoke stack. The casting 50 has in its surrounding the exhaust nozzle 51 an annular chamber 53 for live 90 steam with an entrance connection 54 for a steam pipe and is provided with upwardly extending discharge nozzles 55 and it will be understood that by proper regulation of the steam supplied to this chamber the draft 95 and circulation of the hot gases may be accurately controlled. Secured to the exhaust nozzle casting 50 above the casting 47 by means of the projecting lugs 56 there is a surrounding conical baffle 57 extending upwardly and outwardly towards the conical baffle 43 but having a sufficient circularly arranged opening between its upper margin and 43 for the passage of the products of combustion. This arrangement causes the 100 products of combustion rising through the center portion of the boiler to pass outwardly towards the space in the smoke box over the superheater elements before passing to the smoke stack and avoids localization of 110 the draft and consequent uneven heating.

Having thus described the invention what is claimed as new and desired to be secured by Letters Patent is:

1. In a vertical boiler having lower and upper tube sheets and tubes and flues connecting said sheets, the combination with a top extension from said boiler and a cover plate forming a chamber or smoke box for the gases of combustion with an outlet in the cover plate, of a conical baffle in said box surrounding said outlet and extending downwardly, an exhaust pipe in said chamber having a nozzle directed towards said outlet and having a plurality of depending lugs resting on said upper tube sheet, and an oppositely turned conical baffle secured to said nozzle over said exhaust pipe.

2. In a vertical boiler having lower and upper tube sheets and tubes and flues con-

necting said sheets, the combination with the top extension from said boiler and a cover plate forming a chamber or smoke box for the gases of combustion with an outlet in the 5 cover plate, of a hollow casting in said smoke box having an inlet adapted to be connected to an exhaust pipe and having an opening directed towards said outlet, a nozzle secured in said opening having a plurality of exterior radial lugs, and a conical 10 deflector secured to said lugs.

3. In a vertical boiler having a cylindrical shell, a lower and an upper tube sheet, tubes and flues connecting said sheets, the 15 combination of a top extension from said

boiler with a cover plate forming a chamber or smoke box for the gases of combustion with an outlet for smoke in its center and an exhaust nozzle below and directed towards said outlet and having curved vanes 20 to produce a whirling action of the exhaust steam and gases passing out through said outlet and jet openings surrounding said exhaust nozzle opening and directed towards said outlet and means for supplying live 25 steam to said jet openings to augment the exhaust.

In testimony whereof I hereunto affix my signature.

ROBERT N. MILLER.
